(57) **ABSTRACT**

A golf club head according to an embodiment includes a face having a ball striking surface and a back surface. The back surface of the face has a thick portion located at a generally center portion thereof in a direction from the toe toward the heel, a thin portion located around the thick portion, and a tapered portion located between the thick portion and the thin portion. The thick portion has a first width which is a width in a heel-toe direction, and a second width which is a width in a sole-top direction and is larger than the first width, and the thick portion also has a first thickness. The thin portion has a second thickness smaller than the first thickness. The tapered portion has a thickness reduced from the side of the thick portion toward the side of the thin portion.

GOLF CLUB HEAD AND GOLF CLUB

This nonprovisional application is based on Japanese Patent Application No. 2016-070439 filed on Mar. 31, 2016, with the Japan Patent Office, the entire contents of which are hereby incorporated by reference.

BACKGROUND OF THE INVENTION**Field of the Invention**

The present invention relates to a golf club head and a golf club.

Description of the Background Art

Conventionally, in order to allow a golf club to coestablish striking performance and durability, a structure of a face is known in which a face portion is partially varied in thickness.

Japanese Patent Laying-Open No. 2006-175135 describes a golf club having a face portion with a back surface having a thin portion and a thick portion. The thick portion is provided near the center of the face portion. A width of the thick portion in a direction from the heel side toward the toe side is narrower than a width thereof in a direction from the top side toward the sole side.

SUMMARY OF THE INVENTION

The golf club described in Japanese Patent Laying-Open No. 2006-175135 can improve a center portion of a face in rigidity while reducing a difference between a flying distance in a case of an off-center shot and a flying distance in a case of striking a ball at a sweet spot (i.e., a difference between a COR of the toe side or heel side of the face portion and a COR of the sweet spot).

The golf club described in Japanese Patent Laying-Open No. 2006-175135, however, has the face portion abruptly varying in shape at a boundary between the thin portion and the thick portion. Accordingly, the golf club described in Japanese Patent Laying-Open No. 2006-175135 will have stress concentration at the boundary between the thin portion and the thick portion. As a result, the golf club described in Japanese Patent Laying-Open No. 2006-175135 may have the boundary between the thin portion and the thick portion damaged when striking a ball. Furthermore, the golf club described in Japanese Patent Laying-Open No. 2006-175135 is required to have the thick portion to have a thickness of some extent to improve durability. As a result, the golf club described in Japanese Patent Laying-Open No. 2006-175135 would have a head having an increased overall weight.

The present invention has been made in view of such a problem in conventional art. That is, the present invention contemplates a golf club head and golf club which can reduce a difference between a flying distance in a case of an off-center shot and a flying distance in a case of striking a ball at a sweet spot while maintaining high repulsion performance at the sweet spot and can also maintain durability while minimizing an increase in weight.

A golf club head according to the present invention includes a face having a ball striking surface and a back surface opposite to the ball striking surface. The back surface of the face has a thick portion located at a generally center portion thereof in a direction from the toe of the golf club head toward the heel of the golf club head, a thin portion located around the thick portion, and a tapered

portion located between the thick portion and the thin portion. The thick portion has a first width which is a width in a direction from the heel of the golf club head toward the toe of the golf club head, and a second width which is a width in a direction from the sole of the golf club head toward the top of the golf club head and larger than the first width, and the thick portion also has a first thickness. The thin portion has a second thickness smaller than the first thickness. The tapered portion has a thickness reduced from the side of the thick portion toward the side of the thin portion.

The foregoing and other objects, features, aspects and advantages of the present invention will become more apparent from the following detailed description of the present invention when taken in conjunction with the accompanying drawings.

BRIEF DESCRIPTION OF THE DRAWINGS

FIG. 1A is a front view of a golf club head according to a first embodiment.

FIG. 1B is a rear view of the golf club head according to the first embodiment.

FIG. 2A is a cross-sectional view of the golf club head according to the first embodiment taken along a line IIa-IIa.

FIG. 2B is a cross-sectional view of the golf club head according to the first embodiment taken along a line IIb-IIb.

FIG. 2C is an enlarged view of a vicinity of a sole portion in FIG. 2A.

FIG. 3 is a rear view of a golf club head according to a comparative example.

FIG. 4 is a cross sectional view of the golf club head according to the comparative example taken along a line IV-IV.

FIG. 5 represents an effect of a difference between a first thickness and a second thickness on a COR of a face portion on a heel side and a toe side.

FIG. 6 represents an effect of the difference between the first thickness and the second thickness on a COR of the face portion at a sweet spot.

FIG. 7 represents a relationship between a third width and a maximum value of a VM stress at the face portion.

FIG. 8 is a rear view of a golf club head according to a second embodiment.

FIG. 9A is a rear view of one example of a golf club head according to a third embodiment.

FIG. 9B is a front view of another example of the golf club head according to the third embodiment.

FIG. 10 shows a golf club according to the present invention.

DESCRIPTION OF THE PREFERRED EMBODIMENTS

Hereafter, embodiments will be described with reference to the drawings. In the figures, identical or corresponding components are identically denoted. Furthermore, the embodiments described below may at least partially be combined together, as desired.

First Embodiment

Hereinafter, a configuration of a golf club head and golf club according to a first embodiment will be described.

A golf club head 1 according to the first embodiment is an iron golf club head.

Golf club head 1 is, for example, a cavity back type iron head. FIG. 1A is a front view of golf club head 1 according to the first embodiment. FIG. 1B is a rear view of golf club head 1 according to the first embodiment. Golf club head 1 according to the first embodiment is formed for example by casting.

With reference to FIGS. 1A and 1B, and 2A and 2B, golf club head 1 includes a hosel 21 receiving a shaft there-through, and a head body 20. Head body 20 has a face portion 28, a heel portion 24a, a toe portion 24b, a sole portion 24c, and a top edge portion 24d.

Heel portion 24a is a portion connecting a lower end of hosel 21 and sole portion 24c together. Toe portion 24b is a portion connecting sole portion 24c and top edge portion 24d at a position opposite to heel portion 24a. Sole portion 24c is a portion constituting a bottom portion of golf club head 1. Top edge portion 24d is a portion constituting an upper edge portion of head body 20.

Face portion 28 is further composed of a face surface 28a and a back face surface 28b. Face surface 28a forms a ball striking surface. Back face surface 28b is a surface opposite to face surface 28a.

On the back side of head body 20, an edge portion 22 is formed. Edge portion 22 surrounds a periphery of the back surface side of head body 20. Edge portion 22 defines a cavity 23. As a result, the back side of head body 20 has a shape concaved toward the ball striking surface.

Edge portion 22 is provided with an undercut 29. Undercut 29 is in the form of a groove along back face surface 28b. Undercut 29 is provided in each of heel portion 24a, toe portion 24b, sole portion 24c, and top edge portion 24d.

FIG. 2A is a cross-sectional view taken along a line IIa-IIa in FIG. 1A, and is a cross-sectional view of head body 20 cut at a score line center perpendicularly to a score line (hereinafter referred to as a "reference cross section").

Undercut 29 for example has a width of 6.0 mm or more and 8.5 mm or less on the side of sole portion 24c for a number six iron. The thinnest portion of sole portion 24c, that is, a distance ST between a bottom surface of undercut 29 and a sole surface of sole portion 24c (i.e., a surface of sole portion 24c opposite to a side provided with undercut 29) is preferably 1.5 mm or more and 2.0 mm or less, taking into consideration high repulsion improved by deflection of sole portion 24c and the durability of sole portion 24c.

As shown in FIGS. 1A and 2A, back face surface 28b has a thick portion 25, a tapered portion 26, and a thin portion 27. Thick portion 25, in a toe-heel direction (a direction from toe portion 24b toward heel portion 24a), is located around a center of face portion 28. Specifically, as shown in FIG. 1A, thick portion 25 is provided such that a center thereof in the toe-heel direction is at a position passing through the score line center. Furthermore, in a top-sole direction (a direction from top edge portion 24d toward sole portion 24c), as shown in FIGS. 1B and 2A, thick portion 25 is provided in contact with sole portion 24c.

FIG. 2C is an enlarged view of a vicinity of sole portion 24c in FIG. 2A. As shown in FIG. 2C, thick portion 25 is connected to sole portion 24c via a fillet portion 30 connecting a wall surface of undercut 29 on the side of the sole and back face surface 28b. Thick portion 25 has a lower end matching an end 30a of fillet portion 30 closer to the face.

On back face surface 28b, thin portion 27 is located around thick portion 25. Tapered portion 26 is located between thick portion 25 and thin portion 27.

Referring to FIG. 1B, thick portion 25 has a first width W1 and a second width W2. First width W1 is a maximum value of a width of thick portion 25 in a direction from the

heel portion 24a side toward the toe portion 24b side. Second width W2 is a maximum value of a width of thick portion 25 in a direction from the sole portion 24c side toward the top edge portion 24d side. First width W1 is narrower than second width W2.

More specifically, with reference to the reference cross section (see FIG. 2A), second width W2 is a distance between end 30a closer to the face and an intersection point P1 at which a line segment perpendicular to face surface 28a passing through an end point of thick portion 25 closer to top edge portion 24d and a line segment extending from end 30a closer to the face parallel to face surface 28a intersect each other.

Tapered portion 26 has a third width W3. Third width W3 is a distance of a line segment perpendicular to line tangent to a contour of thick portion 25 appearing in the rear view of FIG. 1B, that is sandwiched between a contour of tapered portion 26 and a contour of thick portion 25. Preferably, third width W3 is 2 mm or more 20 mm or less.

Third width W3 may be uniform as long as it has a value within the above range and a maximum value of a total length of thick portion 25 and tapered portion 26 when golf club head 1 set on a horizontal plane such that golf club head 1 has loft and lie angles as set (hereinafter referred to as a "reference position") is cut in the toe-heel direction horizontally is shorter than a maximum value of a total length of thick portion 25 and tapered portion 26 when golf club head 1 in the reference position is cut in the top-sole direction vertically. Third width W3 may be a non-uniform width such that it is increased from the top edge portion 24d side toward the sole portion 24c side. Note that golf club head 1 according to the first embodiment has tapered portion 26 having third width W3 which is a uniform width.

FIG. 2B is a cross-sectional view of golf club head 1 according to the first embodiment taken along a line IIb-IIb shown in FIG. 1B. Thick portion 25 is thicker than thin portion 27 on back face surface 28b. Thick portion 25 has a first thickness T1. Thin portion 27 has a second thickness T2. First thickness T1 is thicker than second thickness T2. First thickness T1 and second thickness T2 have a difference of 0.25 mm or more and 1.50 mm or less, preferably 0.25 mm or more and 1.25 mm or less. Thin portion 27 has a thickness for example of 1.8 mm or more and 3.0 mm or less.

Tapered portion 26 is thicker than thin portion 27 and thinner than thick portion 25 on the back face surface 28b. Specifically, tapered portion 26 has a thickness matching first thickness T1 on the thick portion 25 side and matching second thickness T2 on the thin portion 27 side, and decreasing as it is away from the thick portion 25 side and approaches the thin portion 27 side.

For example, tapered portion 26 is linearly reduced in thickness as it is away from the thick portion 25 side and approaches the thin portion 27 side. Note, however, that the thickness of tapered portion 26 is not limited as such. It suffices that tapered portion 26 has a thickness reduced as it is away from the thick portion 25 side and approaches the thin portion 27 side.

Hereinafter, an effect of golf club head 1 according to the first embodiment will be described, as compared with a comparative example.

FIG. 3 is a rear view of a golf club head according to the comparative example. FIG. 4 is a cross sectional view of the golf club head according to the comparative example taken along a line IV-IV shown in FIG. 3.

As shown in FIGS. 3 and 4, the golf club head according to the comparative example is different from golf club head 1 according to the first embodiment in that the former does not have tapered portion 26.

Golf club head 1 according to the first embodiment with first thickness T1 and second thickness T2 having a difference of 0.5 mm had face portion 28 subjected to measuring a maximum value of a VM stress (Von Mises stress), which indicated 1700 MPa.

Note that VM stress is a value used as a fracture criterion for material. VM stress is calculated by $\{(\sigma_1 - \sigma_2)^2 + (\sigma_2 - \sigma_3)^2 + (\sigma_3 - \sigma_1)^2\}^{1/2}$, where σ_1 , σ_2 , σ_3 represent major stresses in mutually orthogonal three directions.

The golf club head according to the comparative example with first thickness T1 and second thickness T2 having a difference of 4 mm had face portion 28 subjected to measuring a maximum value of a VM stress, which indicated 1924 MPa.

As has been set forth above, golf club head 1 according to the first embodiment has tapered portion 26 between thick portion 25 and thin portion 27. Accordingly, the golf club according to the first embodiment has thick portion 25 and thin portion 27 with their respective surfaces connected via a continuous variation in thickness. Accordingly, a golf club according to the first embodiment, as compared with a golf club according to the comparative example, alleviates stress concentration at a portion connecting thick portion 25 and thin portion 27. As a result, the golf club according to the first embodiment is enhanced in durability despite the small difference between T1 and T2.

Further, the golf club according to the first embodiment that can have face portion 28 provided with tapered portion 26, as described above, to enhance durability allows thick portion 25 to have a reduced thickness. This allows the head to be lighter in weight than the comparative example having face portion 28 composed only of thick portion 25 and thin portion 27.

Hereinafter, an effect of setting a difference between first thickness T1 and second thickness T2 in the first embodiment to 0.25 mm or more and 1.25 mm or less will be described.

FIG. 5 represents an effect of a difference between first thickness T1 and second thickness T2 on a COR of face portion 28 on the heel portion 24a side and the toe portion 24b side. In FIG. 5, the axis of abscissa represents the difference between first thickness T1 and second thickness T2. In FIG. 5, the axis of ordinate represents a ratio of a COR of face portion 28 at a sweet spot and an average value of a COR of face portion 28 on the heel portion 24a side and a COR of face portion 28 on the toe portion 24b side.

As shown in FIG. 5, as the difference between first thickness T1 and second thickness T2 increases, a ratio of the average value of the COR of face portion 28 on the heel portion 24a side and the COR of face portion 28 on the toe portion 24b side to the COR of face portion 28 at the sweet spot increases. In other words, as the difference between first thickness T1 and second thickness T2 increases, a difference between a flying distance in a case of an off-center shot and a flying distance in a case of striking a ball at the sweet spot decreases.

In contrast, when the difference between first thickness T1 and second thickness T2 is 25 mm or more, the ratio of the average value of the COR of face portion 28 on the heel portion 24a side and the COR of face portion 28 on the toe portion 24b side to the COR of face portion 28 at the sweet spot starts to decrease. That is, as the difference between first thickness T1 and second thickness T2 is increased to 1.25

mm or more, the difference between the flying distance in the case of the off-center shot and the flying distance in the case of striking a ball at the sweet spot would be increased.

FIG. 6 represents an effect of the difference between first thickness T1 and second thickness T2 on the COR of face portion 28 at a sweet spot. In FIG. 6, the axis of abscissa represents the difference between first thickness T1 and second thickness T2. In FIG. 6, the axis of ordinate represents the COR of face portion 28 at the sweet spot.

As shown in FIG. 6, as the difference between first thickness T1 and second thickness T2 increases, the COR of face portion 28 at the sweet spot decreases. That is, if the difference between first thickness T1 and second thickness T2 is excessively increased, the flying distance in the case of striking a ball at the sweet spot would decrease.

Thus, when the difference between first thickness T1 and second thickness T2 is 0.25 mm or more and 1.25 mm or less, a difference between a flying distance in a case of striking a ball at a sweet spot and a flying distance in a case of an off-center shot can be suppressed and a decrease in the flying distance in the case of striking a ball at the sweet spot can also be suppressed.

Hereinafter, an effect obtained in the first embodiment by setting third width W3 to 2 mm or more and 20 mm or less will be described.

FIG. 7 represents a relationship between third width W3 and a maximum value of a VM stress in face portion 28. In FIG. 7, the axis of abscissa represents third width W3. In FIG. 7, the axis of ordinate represents a maximum value of a VM stress in face portion 28.

As shown in FIG. 7, as third width W3 increases, the maximum value of the VM stress in face portion 28 decreases. Specifically, when third width W3 is 1 mm, the maximum value of the VM stress in face portion 28 is 1967.8 MPa, and when third width W3 is 2 mm, the maximum value of the VM stress in face portion 28 is 1839.1 MPa.

When golf club head 1 is formed using stainless steel, which is a material normally used for a golf club head, and third width W3 is less than 2 mm, the maximum value of the VM stress would exceed a value tolerable by the material of golf club head 1. In contrast, when third width W3 is 2 mm or more, the maximum value of the VM stress is within a range tolerable by the material of golf club head 1. Thus, it is preferable that third width W3 be 2 mm or more.

Golf club head 1 has sole portion 24c and top edge portion 24d with a distance normally of about 40 mm therebetween. Accordingly, it is difficult to set third width W3 to 20 mm or more. Thus, it is preferable that third width W3 be 20 mm or less.

From the above, by setting third width W3 to 2 mm or more and 20 mm or less, the maximum value of the VM stress caused in face portion 28 can fall within a range tolerable by a material used to produce golf club head 1.

Hereinafter, an effect of providing thick portion 25 in contact with sole portion 24c will be described.

Enhancing golf club head 1 in durability requires improving face portion 28 in durability as well as improving sole portion 24c in durability. By providing a thickness, that is, fillet portion 30, to a boundary portion between face portion 28 and sole portion 24c, a VM stress in sole portion 24c on the side of the sole surface can be reduced. Accordingly, by extending thick portion 25 from sole portion 24c via fillet portion 30, sole portion 24c can be enhanced in durability.

In particular, when undercut 29 is provided, extending thick portion 25 from an upper surface of sole portion 24c located in undercut 29 allows sole portion 24c to have a

reduced thickness. This can enhance sole portion **24c** in durability while maintaining high repulsion attributed to undercut **29**.

Furthermore, it is preferable that golf club head **1** according to the first embodiment satisfy a relationship of (first width $W1+2\times$ third width $W3$)/(taper's upper end level) ≤ 0.5 . In other words, it is preferable that a total width of thick portion **25** and tapered portion **26** in the direction from the sole portion **24c** side toward the top edge portion **24d** side be twice a total width of thick portion **25** and tapered portion **26** in the direction from the heel portion **24a** side toward the toe portion **24b** side or more.

The taper's upper end level is a length from sole portion **24c** to a top portion of tapered portion **26**. More specifically, with reference to the reference cross section (see FIG. 2A) the taper's upper end level is a distance between end **30a** closer to the face and an intersection point **P2** at which a line segment perpendicular to face surface **28a** passing through an end point of tapered portion **26** closer to top edge portion **24d** and a line segment extending from end **30a** closer to the face parallel to face surface **28a** intersect each other.

According to the findings obtained by the inventors, (first width $W1+2\times$ third width $W3$)/(taper's upper end level) has a value having a strong negative correlation with the ratio of the COR of face portion **28** at the sweet spot and the average value of the COR of face portion **28** on the heel portion **24a** side and the COR of face portion **28** on the toe portion **24b** side.

For example, when (first width $W1+2\times$ third width $W3$)/(taper's upper end level) had a value of 0.23, the ratio of the COR of face portion **28** at the sweet spot and the average value of the COR of face portion **28** on the heel portion **24a** side and the COR of face portion **28** on the toe portion **24b** side was 98.6%.

Accordingly, (first width $W1+2\times$ third width $W3$)/(taper's upper end level) having a value 0.5 or less can further reduce a difference between a flying distance in a case of an off-center shot and a flying distance in a case of striking a ball at the sweet spot.

A golf club **100** is obtained by fixing a shaft **10** to golf club head **1** configured as described above. FIG. 10 is an overall view of golf club **100** including golf club head **1** according to the first embodiment. Such golf club **100** can provide high repulsion and durability.

Second Embodiment

Hereinafter, a configuration of a golf club head **2** according to a second embodiment will be described. A difference from the first embodiment will mainly be described.

FIG. 8 is a rear view of golf club head **2** according to the second embodiment. As shown in FIG. 8, golf club head **2** according to the second embodiment is different from golf club head **1** according to the first embodiment in that face portion **28** has thick portion **25** out of contact with sole portion **24c**.

It is preferable that golf club head **2** according to the second embodiment, as well as the first embodiment, also satisfy the relationship of (first width $W1+2\times$ third width $W3$)/(taper's upper end level) ≤ 0.5 . In other words, it is preferable that a total width of thick portion **25** and tapered portion **26** in the direction from the sole portion **24c** side toward the top edge portion **24d** side be twice a total width of thick portion **25** and tapered portion **26** in the direction from the heel portion **24a** side toward the toe portion **24b** side or more. The taper's upper end level is a distance from

end **30a** closer to the face to intersection point **P2**, similarly as has been described in the first embodiment.

In golf club head **2** according to the second embodiment, for example when (first width $W1+2\times$ third width $W3$)/(taper's upper end level) has a value of 2.09, the ratio of the COR of face portion **28** at the sweet spot and the average value of the COR of face portion **28** on the heel portion **24a** side and the COR of face portion **28** on the toe portion **24b** side was 98.1%.

When (first width $W1+2\times$ third width $W3$)/(taper's upper end level) has a value of 1.16, the ratio of the COR of face portion **28** at the sweet spot and the average value of the COR of face portion **28** on the heel portion **24a** side and the COR of face portion **28** on the toe portion **24b** side was 98.3%.

When (first width $W1+2\times$ third width $W3$)/(taper's upper end level) has a value of 0.87, the ratio of the COR of face portion **28** at the sweet spot and the average value of the COR of face portion **28** on the heel portion **24a** side and the COR of face portion **28** on the toe portion **24b** side was 98.4%.

When (first width $W1+2\times$ third width $W3$)/(taper's upper end level) has a value of 0.41, the ratio of the COR of face portion **28** at the sweet spot and the average value of the COR of face portion **28** on the heel portion **24a** side and the COR of face portion **28** on the toe portion **24b** side was 98.6%.

Thus, golf club head **2** according to the second embodiment with (first width $W1+2\times$ third width $W3$)/(taper's upper end level) having a value 0.5 or less can also further reduce a difference between a flying distance in a case of an off-center shot and a flying distance in a case of striking a ball at the sweet spot.

Third Embodiment

A configuration of a golf club head according to a third embodiment will be described. A difference from the other embodiments will mainly be described.

The golf club head according to the third embodiment is a wood type head, for example. FIG. 9A is a rear view of a golf club head **3a** according to the third embodiment.

Golf club head **3a** has a face portion **38**. Furthermore, golf club head **3a** has a heel portion **34a**, a toe portion **34b**, a sole portion **34c**, and a crown portion **34d**. Face portion **38** has a back surface with a thick portion **35**, a tapered portion **36**, and a thin portion **37**.

As shown in FIG. 9A, wood type golf club head **3a** may also have thick portion **35** and tapered portion **36** extended from sole portion **34c**. FIG. 9B is a front view of another example of the golf club head according to the third embodiment. As shown in FIG. 9B, a golf club head **3b** according to the other example may have thick portion **35** and tapered portion **36** formed at the face only in a vicinity of the sweet spot.

While the present invention has been described in embodiments, it should be understood that the embodiments disclosed herein are illustrative and non-restrictive in any respect. The scope of the present invention is defined by the terms of the claims, and is intended to include any modifications within the meaning and scope equivalent to the terms of the claims.

What is claimed is:

- An iron golf club head comprising:
a face having a ball striking surface and a back surface opposite to the ball striking surface,

9

a sole portion constituting a bottom portion of the iron golf club head,
 an edge portion provided at the back surface and defining
 a cavity, the edge portion having an undercut portion,
 the back surface of the face having a thick portion located
 at a generally center portion thereof in a direction from
 a toe of the golf club head toward a heel of the golf club
 head, a thin portion located around the thick portion,
 and a tapered portion located between the thick portion
 and the thin portion,
 the thick portion having a first width which is a width in
 a direction from the heel of the golf club head toward
 the toe of the golf club head, and a second width which
 is a width in a direction from the sole of the golf club
 head toward a top of the golf club head and larger than
 the first width, the thick portion also having a first
 thickness,
 wherein the thick portion extends from an upper surface
 the sole portion located in the undercut portion,
 wherein the thick portion is connected to the sole portion
 via a fillet portion,

10

the thin portion having a second thickness smaller than
 the first thickness, wherein the second thickness of the
 thin portion is a constant thickness,
 the tapered portion having a thickness reduced from a side
 of the thick portion toward a side of the thin portion,
 and

at least a part of the thick portion being located in the
 undercut portion.

2. The iron golf club head according to claim 1, wherein
 the first thickness and the second thickness have a difference
 of 0.25 mm or more and 1.25 mm or less.

3. The iron golf club head according to claim 1, wherein:
 the tapered portion has a third width; and
 the third width is 2 mm or more and 20 mm or less.

4. The iron golf club head according to claim 1, wherein:
 the tapered portion has a third width; and
 a value of the first width plus the third width multiplied by
 two, divided by a length from the sole to a top portion
 of the tapered portion, is 0.5 or less.

5. An iron golf club comprising the iron golf club head
 according to claim 1.
